HIGH-FREQUENCY ANTENNA

Rody Miller, Akron, Ohio

Application December 2, 1948, Serial No. 62,997

4 Claims. (Cl. 250—33)

1

This invention relates to high frequency antennas, and, more particularly, is concerned with television receiving antennas.

Heretofore, the conventional television receiving antenna has been of the dipole type and has been employed with one or more directors or reflectors. It is the conventional practice to install these antennas as high as possible in order that they can best receive the high frequency television waves which are known to possess characteristics whereby the receiving antenna must be in substantially the "line of sight" of the transmitting antenna, or must be so positioned with respect to reflecting surfaces as to pick up the transmitted signal. This has necessitated in conjunction with the usual television receiving set a rather grotesque and unsightly antenna array which is often objectionable from an appearance standpoint, to say nothing of the expense and danger of installation. It has also resulted in particularly elaborate antenna arrays in outlying districts remote from television transmitting stations which arrays are even more expensive and difficult to install.

It is the general object of my invention to avoid and overcome the foregoing and other difficulties of and objections to prior known practices by the provision of an improved high frequency antenna characterized by inexpensiveness, high efficiency, and ease of installation.

Another object of my invention is the provision of a television antenna of the simple dipole type utilizing helically wound wire coils in association with each leg of the dipole.

The foregoing objects of my invention, and other objects which will become apparent as the description proceeds, are achieved by the provision of a high frequency wave antenna comprising a support, dipoles carried on the support in insulated relation to each other and to the support, each leg of the dipole being substantially equal in length to the other and to one-quarter of the wave length of the wave being handled by the antenna, or any full number multiple thereof, electrical leads extending from each leg of the dipole, a helical coil of wire surrounding each leg of the dipole over substantially its full length, means insulating each coil from its dipole leg, the total length of the wire in each coil being preferably a full number multiple of the length of the dipole leg, and the diameter of each coil being greater than the diameter of each leg of the dipole.

For a better understanding of my invention, reference should be had to the accompanying drawing, wherein

Fig. 1 is a front elevation, partly broken away, of a typical embodiment of a high frequency antenna incorporating the principles of the invention;

2

Fig. 2 is an enlarged sectional view taken substantially on line 2—2 of Fig. 1;

Fig. 3 is a diagrammatic showing of a folded dipole incorporating the principles of the invention;

Fig. 4 is a perspective view of a folded dipole made from a slotted tube;

Fig. 5 is a view similar to Fig. 3 but shows a modification thereof; and

Fig. 6 is a side elevation illustrating a stacked array of different frequency antennas utilizing the invention.

Having particular reference to the drawings, the numeral 10 indicates generally a support of any suitable type, for example, comprising metal pipe or tubing connected by a coupling 12 to a T fitting 14. A second T fitting 16 is secured to one leg of the T fitting 14, and secured in the ends of the T fitting 16 are pins 18 which are received in suitable holes in insulator spools 20. Fitting over each insulating spool 20 is a metal tube 22 forming a leg of the two-leg dipole thus produced, it being understood that the tubes 22 are cut to a length equal to each other and to any full number multiple of one-quarter wave length of the wave frequency being handled. Usually each tube 22 is cut to a length substantially equal to only a single one-quarter wave length. Electrical leads 24 are connected to the dipole legs 22 in accord with the usual practice.

Associated with each of the legs of the dipole is a helical coil 26 of wire having, as indicated, a diameter somewhat greater than the diameter of the tube 22, and being insulated therefrom by circumferentially spaced insulating strips 28 which extend substantially the full length of the tubes 22. It will be noted that each coil 26 likewise extends substantially the full length of its associated tube 22, and the overall length of the wire in each coil 26 is preferably made a full number multiple of one-quarter wave length of the high frequency wave being received. The coils 26 are not connected to anything, and while the exact principles of operation are not fully understood, it is believed that the high frequency waves picked up in the coils 26 are induced into the dipole leg 22.

The dipole array heretofore described is usually employed in conjunction with a substantially conventional reflector which takes the form of a short bar or tube 30 connected to the other leg of the T 14 and terminating in a T 32 which in turn carries reflector tubes 34. The spacing between the reflector tubes 34 and the dipole legs 22 is conventional.

The ends of the tubes 22 are preferably rounded and closed, as indicated at 36, and this can be done either by upsetting the end of the tube 22 or by providing an auxiliary cap of similar character.

I have discovered that a high frequency antenna constructed in the manner described and when employed to receive television signals will give surprisingly unexpected and unusual results. This is not only true in outlying districts where I have found that my improved antenna will pull in signals better than much more expensive and elaborate arrays, but is also true in locations closer to the broadcasting station. I have found, for example, that my improved antenna can often be merely hung in the room in which the television receiver is located, and does not even have to be put up on the roof in order to pick up an excellent picture. Tests with conventional television antennas in similar locations have failed to produce a satisfactory picture, or any picture at all.

Having reference to Fig. 3 of the drawings, the numeral 40 indicates generally and diagrammatically an open-center folded dipole having leads 42. The open-center folded dipole can be made if desired by slotting a tube 44, as shown in Fig. 4, almost to its end. Coils 46 are wound around the legs of the dipole either around both legs simultaneously as shown in Fig. 3, or around each leg separately as seen in Fig. 5.

In Fig. 6 I have shown a stacked array of antennas 48, 50, and 52 constructed in accord with the invention and cut to different frequencies. Each antenna can be directed toward the transmitting station broadcasting its frequency by providing pivotal flange supports 54 which can be adjusted to and locked at the desired angle.

It should be mentioned that some of the advantages of the invention are realized when using a single leg type of antenna in association with a surrounding coil as described, and connecting this single leg antenna to one of the antenna posts on the receiver with the other antenna post on the receiver being connected to ground. This type of antenna when employed within a dozen or so miles of the transmitting station can be used right on top or behind the television receiver to pull in satisfactory pictures without the cost and complication of an outside antenna.

It will be recognized from the foregoing that I have achieved the various objects of my invention, and have provided an improved, efficient, relatively inexpensive and easily installed high frequency antenna particularly adapted for television use. I should note that the dipole legs of my antenna can be made from bars or rods, rather than tubing. I have also found from tests to date that the diameter of the coils 26 relative to the diameter of the dipole legs does not appear to be too important, but I preferably make the differences in diameter equal to a fraction of the wave length being received.

The term dipole as employed in the claims is intended to cover both folded and straight dipoles.

While certain representative embodiments and details have been shown for the purpose of illustrating the invention, it will be apparent to those skilled in this art that various changes and modifications may be made therein without departing from the spirit or scope of the invention.

I claim:

1. A high frequency wave antenna comprising a support, a two-leg dipole carried on the support, each leg in insulated relation to each other and to the support, each leg of the dipole being substan-

tially equal in length to one quarter of the operating wave-length, electrical leads extending from each leg of the dipole, a helical coil of wire surrounding each leg of the dipole over substantially its full length, strip means spaced circumferentially around each leg of the dipole and insulating the coil therefrom, the total length of the wire in each coil being a full number multiple of the length of the dipole leg, and the diameter of each coil being greater than the diameter of each leg of the dipole.

2. A high frequency wave antenna comprising a support, a two-leg dipole carried on the support, each leg in insulated relation to each other and to the support, each leg of the dipole being substantially equal in length to the other and to one quarter of the wave-length of the operating length wave or a full number multiple thereof, electrical leads extending from each leg of the dipole, a helical coil of wire surrounding each leg of the dipole over substantially its full length, strip means spaced circumferentially around each leg of the dipole and insulating the coil therefrom, the total length of the wire in each coil being a full number multiple of the length of the dipole leg, and the diameter of each coil being greater than the diameter of each leg of the dipole.

3. A high frequency wave antenna comprising a support, a two-leg dipole carried on the support, each leg in insulated relation to each other and to the support, each leg of the dipole being substantially equal in length to the other and to one quarter of the wave-length of the wave being handled by the antenna or a full number multiple thereof, electrical leads extending from each leg of the dipole, a helical coil of wire surrounding each leg of the dipole over substantially its full length, means insulating each coil from its dipole leg, the total length of the wire in each coil being a full number multiple of the length of the dipole leg, and the diameter of each coil being greater than the diameter of each leg of the dipole.

4. A high frequency wave antenna comprising a support, a two-leg dipole carried on the support, each leg in insulated relation to each other and to the support, each leg of the dipole being substantially equal in length to the other and to one quarter of the wave-length of the wave being handled by the antenna or a full number multiple thereof, electrical leads extending from each leg of the dipole, a helical coil of wire surrounding each leg of the dipole over substantially its full length, and means insulating each coil from its dipole leg.
